UNITED STATES PATENT OFFICE.

JAMES BEARD, OF PASADENA, CALIFORNIA.

AUTOMATIC WATER HEATER.

1,420,513.

Specification of Letters Patent. Patented June 20, 1922.

Application filed December 6, 1920. Serial No. 428,777.

To all whom it may concern:

Be it known that I, JAMES BEARD, a subject of the King of Great Britain, residing at Pasadena, in the county of Los Angeles 5 and State of California, have invented new and useful Improvements in Automatic Water Heaters, of which the following is a specification.

This invention relates to automatic water heaters and has for its object to provide controlling means for a device of this kind wherein mechanism actuated by the flow of liquid and the cut-off valve for the fuel operated by said mechanism are to be contained 15 within a single casing so as to provide an extremely simple and compact structure.

The invention will be readily understood from the following description of the accompanying drawings, in which:

20 Fig. 1 is a side elevation showing the portion of a water heater having the improved controlling means applied thereto.

Fig. 2 is a plan view of the controlling device.

25 Figs. 3, 4 and 5 are vertical sections on the lines 3—3, 4—4 and 5—5 of Fig. 2.

The water heater may be of any usual construction, including casing 1, mounted upon a pedestal 2 and containing any usual 30 type of burner (not shown), the water inlet is shown at 3 and the fuel inlet for the burner is shown at 4.

The controlling mechanism for the fuel adapted to permit the supplying of the fuel 35 to the burner when water is withdrawn from the heater, consists of a housing 5 having vertical bores 6 and 7 arranged alongside of one another. Bore 7 terminates at its base in a conduit 8, to which is attached the water supply pipe 9 and a conduit 10 40 communicates with bore 7 above the base thereof. This conduit is connected to the water supply pipe 3 leading to the water heater.

45 A piston 11 is mounted in bore 7 and is normally seated at the base thereof by means of a coil spring 12 received around the piston rod 13, which projects through the top of casing 5, preferably through a suitable 50 stuffing box 14.

When the piston is seated at the base of bore 7 by the action of spring 12, conduit 10 is shut off from conduit 8, but when the water supply to the water heater is dis- 55 charged as by opening a faucet, the pressure of the water in the conduit 8 will raise pis-

ton 11 against the action of its spring so as to permit the flow of the water from conduit 8 to conduit 10 and thence to the water heater. When the discharge of water again ceases, the pressure against the opposite faces of the piston will again be balanced and spring 12 will again seat the piston.

The movement of the piston as thus described is adapted to actuate the cut-off valve 65 for the fuel supply. For this purpose a fuel inlet 15 communicates with the bore 6 and a fuel outlet 16 is arranged in alignment therewith, the fuel inlet being connected to a fuel supply pipe 17 and the fuel outlet being connected to the pipe 4 leading to the burner. The supply pipe may be provided with any usual manually operated cut-off valve 18.

A valve rod 19 is slidable within bore 6, 75 and when seated is adapted to shut off communication between inlet 15 and outlet 16 and thereby stop the supply of fuel to the burner. This valve rod is adapted to be raised when piston 11 is raised so as to permit the supply of fuel to the burner through inlet 15 and outlet 16 whenever water is withdrawn from the heater.

As an instance of this arrangement, piston rod 13 projects beyond its stuffing box 85 14 and is provided with a laterally bent end 20 received in a slot provided in the end of valve rod 19. A leaf spring 22 in this slot, beneath the end of the piston rod, yieldably urges the latter upwardly within the slot 90 and a nut 23, threaded onto the end of the valve rod, is adapted to adjust the piston rod with relation to the valve rod against the tension of spring 22.

It will be noted that the construction as 95 thus set forth provides a compact arrangement wherein the fuel supply is started whenever water is withdrawn from the heater, and is shut off as soon as the withdrawal of water ceases.

100

I claim:

1. An automatic valve for water heaters comprising a body having a water conduit and a fuel conduit, a valve normally urged to closed position for preventing the flow of 105 water through the water conduit, but adapted to move to open position when the pressure of the water at opposite sides of the valve is unequal, said valve including a rod projecting beyond the body and having an 110 angularly bent terminal, a second valve movable in the body to control the passage of

fuel through the fuel conduit, said second valve having a slotted stem projecting from the body and receiving the bent terminal of the rod whereby movement of the first valve 5 to open or closed position will effect a corresponding movement of the second valve.

2. An automatic valve for water heaters comprising a body having a water conduit and a fuel conduit, a valve normally urged 10 to closed position for preventing the flow of water through the water conduit, but adapted to move to open position when the pressure of the water at opposite sides of the valve is unequal, said valve including a rod 15 projecting beyond the body and having an angularly bent terminal, a second valve mov-

able in the body to control the passage of fuel through the fuel conduit, said second valve having a slotted stem projecting from the body and receiving the bent terminal of 20 the rod whereby movement of the first valve to open or closed position will effect a corresponding movement of the second valve, a leaf spring interposed between the rod terminal and valve stem, and a nut threaded 25 on the valve stem and engageable with the rod terminal for adjusting the position of the rod within the stem whereby the relative positions of the two can be varied.

In testimony whereof I have signed my 30 name to this specification.

JAMES BEARD.
